US0D1065231S

(12) **United States Design Patent** (10) Patent No.: **US D1,065,231 S**
(45) Date of Patent: ** Mar. 4, 2025

(54) **DISPLAY SCREEN OR PORTION THEREOF WITH GRAPHICAL USER INTERFACE**

(71) Applicant: **Apple Inc.**, Cupertino, CA (US)

(72) Inventors: **Thorsten Adam**, Hamburg (DE); **Sebastian Boltz**, Elmshorn (DE); **Sascha Höhne**, Rellingen (DE); **Soeren Kelling**, Rellingen (DE); **Rene Tuerschmann**, Rellingen (DE); **Mirko Wannemacher**, Rellingen (DE); **Jennifer Wien**, Pinneberg (DE)

(73) Assignee: **Apple Inc.**, Cupertino, CA (US)

(**) Term: **15 Years**

(21) Appl. No.: **29/886,563**

(22) Filed: **Mar. 9, 2023**

(51) LOC (15) Cl. **14-04**

(52) U.S. Cl.

USPC **D14/485**

(58) **Field of Classification Search**

USPC **D14/485-495**

(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines illustrate a display screen or portion thereof, and form no part of the claimed design.

1 Claim, 1 Drawing Sheet
